FISH LURE

James F. Gondeck, Niles, Mich.

Application December 3, 1956, Serial No. 44,019

Term of patent 14 years

(Cl. D31—4)

FIG. 1

FIG. 2

FIG. 3

I claim:

The ornamental design for a fish lure, substantially as shown.
